(57) CLAIM

The ornamental design for a packing box, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a packing box of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front perspective view thereof; and,

FIG. 8 is a rear perspective view thereof.

The broken lines in the drawings are shown for the purpose of illustrating parts of the article that form no part of the claimed design.

Salonpas® is a registered trademark from Hisamitsu Pharmaceutical Co., Inc. forming part of the claimed design.

1 Claim, 8 Drawing Sheets
